MATCH BOOK HOLDER

Harry Cohen, Chicago, Ill.

Application February 24, 1941, Serial No. 380,379

3 Claims. (CL 206—29)

My invention relates to holders for match books, and more particularly to a device which is adapted to be mounted or attached to the wall in a home, office or other place, and my main object is to provide a holder which makes the match book easy to find and provides a fixed place for the same.

A further object of the invention is to provide a holder which can accommodate a match book of large capacity, so that a plentiful supply of matches may be kept in the holder if desired.

Another object of the invention is to provide a holder which has simple and efficient means for mounting the match book therein and retaining the same firmly in place.

A further object of the invention is to include the novel holder means for easily replacing an exhausted match book with a new one.

An important object of the invention is to design the novel holder along lines of utmost simplicity and with facilities for the display of pictorial or advertising matter.

With the above objects in view and any others which may suggest themselves from the description to follow, a better understanding of the invention may be had by reference to the accompanying drawing, in which—

Fig. 1 is a front elevation of the novel holder;

Fig. 2 is a similar view, partly broken away, showing a match book secured in the holder;

Fig. 3 is a section on the line 3—3 of Fig. 1; and

Fig. 4 is an enlarged section on the line 4—4 of Fig. 2.

With match books widely used both in and out of the home, the situation often presents itself that a match book has been misplaced, lost or given away, and another one is not readily available. Unless match books are kept in various known places in the home or office, expediency will dictate that a place be reserved where one or more match books may be kept and readily found at all times. This method is practiced in some homes or offices, but frequently a chosen place is not handy; or other articles become involved with or conceal the match book or books so kept, so that more or less difficulty is had until a match book is found. Also, where match books are put away or concealed, conditions such as dampness or moisture in the particular place may deteriorate the match heads or abrasive surface to the extent of impairing or entirely destroying the usefulness of the matches; or, friction with other objects may wear the abrasive

down to an extent where it is rendered ineffective.

It has therefore been my intention to provide a holder which eliminates the above difficulties and makes the matches available at all times, in usable condition, and without waste.

In accordance with the foregoing, specific reference to the drawing indicates the main portion of the holder as a metallic plate 10 which may have any suitable or ornamental contour. Preferably, the plate may be reinforced with a bead or other formation 11 at or near its edge to prevent it from warping or becoming otherwise deformed. The plate is perforated in its upper part with two or more holes 12 for the application of nails or screws to secure the holder to a wall or other upright surface.

The plate 10 is elongated, although it may be made shorter if so desired. The bottom of the plate is curled up toward the front to form a channel 13 which is dimensioned to receive the bottom portion of a conventional match book with a snug fit.

The frontal face of the plate 10 receives a long blade 14 of spring metal, such blade extending horizontally a short distance above the channel 13. One end of the blade is pivotally secured to the plate by a friction rivet 15, while the other end is extended a short distance beyond the end of the plate. Preferably, both ends of the blade are rounded as indicated at 17 for purposes of good appearance and handling facility. The blade has a tendency to spring away with its free end from the plate. However, such end of the blade may be secured against the plate by catching the blade under a small hook 18 struck forward from the plate at a point shortly above the normal position of the blade, as indicated in Fig. 2.

The drawing shows the application of an elongated or magazine type of match book 19 to the holder. Obviously, such a match book insures a plentiful supply and the keeping of the match book in the holder for a relatively long period before replacement. Thus, the holder is sufficiently long to accommodate the long or magazine type of match book. Preferably, the holder is extended above the zone of the match book, to afford room for the securing means and for any printed, pictorial or advertising matter intended for display above the match book.

The blade 14 is intended to serve as a retainer for the match book. In order to apply the same to the blade, it is only necessary to swing the blade 14 up to a sufficient extent—as shown by

dotted lines in Fig. 1—to enable the match book to be strung on the blade, the latter assuming a position between the match group and the back wall of the match book, as shown in Fig. 4. The loaded blade is then swung down and the match book fitted at the bottom into the channel 13 of the holder. The blade 14 is now drawn down until it trips the hook 18 and becomes caught thereunder. The tension of the blade now keeps it both locked to the holder and pressed against the back wall of the match book, so as to supplement the channel or pocket 13 in firmly retaining the match book in the holder.

With the holder mounted on the wall or other supporting surface and the match book installed as just described, it is an easy matter to raise and open the cover of the match book and obtain easy access to any match for removal in the ordinary manner. The abrasive strip 20 is exposed and handy for the striking of the match either before or after the cover is closed. After all the matches have been used, the free end of the blade 14 may be released from the hook by a slight downward pressure, so as to enable the blade to be swung up again for the removal and replacement of the exhausted match book. In this particular, it is noted that the free end of the blade extends sufficiently beyond the plate 10 to afford a sufficient hold for the handling or operation of the blade.

It will be evident from the above description that I have provided an article for the above purpose which creates a place in the home, office, or other place where matches may be readily found. By mounting the holder as mentioned, it becomes positioned in the open, and therefore easily seen or found as well as out of the way of moving persons or objects. Also, the matches as placed in the holder are high and dry, so to speak, and therefore remain in good condition as long as they last, receiving no interference, friction, or other influence to impair their quality or usefulness. The mounting of the match book is such that one hand suffices for access to, the removal of, and the striking of the matches. In other words, no part of the match book must be held or steadied in order to enable the cover to be opened. The holder not only accomplishes this purpose, but also places the available and useful portion of the match book in front. Further, the channel or pocket 13 forms a simple, effective, and inconspicuous securing device for the bottom of the match book; and the blade 14 serves as a simple and positive retainer for the same. Thus, the holder provides a plentiful match supply in a place which can easily be found or reached, and in a manner to make the removal and use of the matches easy.

As match books are usually printed with advertising matter, it is seen that such matter may still be printed on the front, top, and inside of the cover, as well as on the matches themselves,

so as to be easily and frequently in sight as the match book is approached or used. Also, the front of the plate 10 may be printed or otherwise marked with pictorial or advertising matter, particularly in the space above the match book and beyond the ends thereof, such spaces being in view at all times.

While I have described the invention along specific lines, various minor changes and refinements may be made without departing from its principle, and I desire to consider all such changes and refinements as coming within the scope and spirit of the appended claims.

I claim:

1. A match book holder comprising a plate adapted to be mounted on a wall, means to support the match book at the bottom, and other means to retain the match book against the plate, said other means comprising a blade pivoted to the plate at one side of the match book to swing from a substantially horizontal normal position in an upward direction along the outer face of the plate, said blade passing through the match book, and means to lock the remote end of the blade to the plate when the blade is in said normal position, said locking means comprising a hook tripped by the blade on its return to the normal position.

2. A match book holder comprising a plate adapted to be mounted on a wall, means to support the match book at the bottom, and other means to retain the match book against the plate, said other means comprising a blade pivoted to the plate at one side of the match book to swing from a substantially horizontal normal position in an upward direction along the outer face of the plate, said blade passing through the match book, and means to lock the remote end of the blade to the plate when the blade is in said normal position, said locking means comprising a hook struck forward from the plate material and tripped by the blade on its return to the normal position.

3. A match book holder comprising a plate adapted to be mounted on a wall, means to support the match book at the bottom, and other means to retain the match book against the plate, said other means comprising a blade pivoted to the plate at one side of the match book to swing from a substantially horizontal normal position in an upward direction along the outer face of the plate, said blade passing through the match book, and means to lock the remote end of the blade to the plate when the blade is in said normal position, said locking means comprising a hook struck forward from the plate material and tripped by the blade on its return to the normal position, and said blade having an inward tension when so hooked to press the back portion of the match book to the plate.

HARRY COHEN.
